United States Patent

Des. 237,467
Patented Nov. 4, 1975

237,467

CONTAINER END

Richard Paul Nightingale, Fox River Grove, and Harlen Edgar Wilkinson, Crystal Lake, Ill., assignors to American Can Company, Greenwich, Conn.

Filed Apr. 22, 1974, Ser. No. 462,768

Term of patent 14 years

Int. Cl. D9—07

U.S. Cl. D9—255

FIG. 1

FIG. 2

FIG. 3

FIG. 1 is a top plan view of a container end showing our new design;

FIG. 2 is an enlarged scale cross-sectional view taken along line 2—2 of FIG. 1; and

FIG. 3 is an enlarged scale cross-sectional view taken along line 3—3 of FIG. 1.

We claim:

The ornamental design for a container end, substantially as shown and described.
